PIVOTED FLOODLIGHT WITH WATERTIGHT
PASSAGEWAY FOR WIRINGPhilip G. Stone, New York, N. Y., assignor to
Stone Manufacturing Co., Elizabeth, N. J.

Application September 26, 1947, Serial No. 776,355

7 Claims. (Cl. 240—3)

1

This invention relates to floodlight assemblies. More particularly it is concerned with adjustably positioned housings for floodlights which are especially adapted for outdoor use in lighting gas stations, parkings lots, loading platforms and the like.

An object of this invention is to provide a device of the character described which includes a housing for an electric lamp socket and floodlight, said housing being pivotally mounted on a base member wherein wiring for said socket extending from said socket through said base member, is completely enclosed and weather proof.

Another object of this invention is to provide in a device of the character described, a housing for a lamp socket, a socket mounted within the housing and substantially filling the housing, said housing being provided with a passageway communicating with a downwardly projecting, enlarged hollow member adapted to be pivotally mounted with respect to a hollow supporting member having a communicating upwardly projecting enlarged hollow member complementary to said first mentioned member, whereby wiring may extend from the rear of said socket, through said passageway, through said enlarged hollow portions and into said hollow support.

Yet another object of this invention is to provide in a device of the character described, a pair of upper and lower members, pivotally connected about a horizontal axis, the upper member being in the form of a lamp socket housing and the lower member being in the form of a combined conduit and support, said members having hollow, intercommunicating portions whereby wiring attached to a lamp socket mounted in the socket housing, may be extended downwardly through said lower member and thereby protected from the weather, yet providing for movement of said upper member with respect to said lower member about said horizontal axis.

Still another object of this invention is to provide in a device of the character described, a floodlight housing pivotally mounted for vertical movement on a hollow support, said pivotal connection being formed with opposed dome-shaped portions communicating with the housing and hollow portions of said support, whereby wiring from a socket mounted in said housing may be extended through said pivotal connection

2

to said support, a gasket being disposed between the opposed dome shaped portions of said housing and said hollow support, whereby said wiring is completely enclosed and protected from the elements without interfering with the adjustability of said housing to any one of a plurality of angular positions.

Still a further object of this invention is to provide in a device of the character described, 10 a substantially tubular shaped lamp housing having mounted thereon a lamp socket substantially filling the interior of said housing, an extension of said housing forming a passageway, a hollow bracket portion extending from said passageway and in communication therewith, a hollow supporting member for said housing from which extends a hollow bracket portion complementary and opposed to said first mentioned bracket portion and communicating with said support, 15 a horizontal member connecting said complementary bracket portions and adapted to provide for adjustable angular movement of said housing with respect to said support, said housing and its bracket portion being formed with 20 a communicating passageway whereby wiring from the rear of the socket mounted in said housing may be extended through said passageway and bracket portions and through said hollow support.

30 Yet a further object of this invention is to provide in a device of the character described, a tubular housing provided at its front end with a flared portion formed with an annular recess on an inner surface of the rim thereof, a socket mounted within the housing and adapted to receive a floodlight bulb having a wall portion complementary to the flared portion of the housing, an annular gasket mounted in the recess in said flared portion of the housing, said gasket being adapted to contact the wall portion of 35 said floodlight bulb thereby sealing the interior of said housing against the ingress of moisture or the like as well as acting as a cushion for the heat expanded bulb when said bulb is illuminated together with means for tiltably supporting said housing on a combined conduit and support, said housing and support having enclosed communicating passageways whereby wiring from said socket may extend through the said tiltably supporting means into said conduit without in-

terfering with the tilting action of said housing with respect to said support.

Another object of this invention is to provide a compact and durable floodlight assembly of the character described, which shall be relatively inexpensive to manufacture, readily assembled and wired, and which shall yet be attractive in appearance, easy to use, practical and efficient to a high degree.

Other objects of this invention will in part be obvious and in part hereinafter pointed out.

The invention accordingly consists in the features of construction, combination of elements, and arrangement of parts which will be exemplified in the construction hereinafter described, and of which the scope of application will be indicated in the following claims.

In the accompanying drawings, in which is shown various possible illustrative embodiments of this invention,

Fig. 1 is a side elevational view of a floodlight assembly embodying the invention;

Fig. 2 is a cross-sectional view taken on the line 2—2 of Fig. 1;

Fig. 3 is a cross-sectional view taken on the line 3—3 of Fig. 2, and showing a socket mounted in the assembly;

Fig. 4 is a cross-sectional view taken on the line 4—4 of Fig. 1; and

Fig. 5 is an elevational view of a pair of floodlight assemblies embodying the invention, mounted on the cross arm of a support.

Referring now in detail to the drawing, 10 designates a floodlight assembly embodying the invention. The same comprises a housing generally designated as 11, and a combined conduit and support pivotally connected to said housing, generally designated as 12.

The housing 11 comprises a generally tubular walled member 13 having the major portion thereof cylindrical and closed at its rear end by a wall 14. Extending from the forward end of member 13, is a flared, part spherical walled portion 15. Extending longitudinally from the lower portion of tubular wall 13 is an enclosed passageway 16 in defining a channel having its open side directly in communicating with the interior of said tubular member. The passageway or channel 16 is formed by a pair of parallel, vertical walls 17, 18 interconnected by a bottom wall 19, and a back wall 20, which is an extension of wall 14.

It will be noted from a consideration of Fig. 4, that the passageway 16 is off centre with respect to the longitudinal axis of tubular member 13, the outer surface of wall 17 defining a plane substantially coinciding with a vertical central plane longitudinally through said tubular member. The front wall 21 of passageway or channel 16 is spaced inwardly of the front end of tubular member 13, as shown in Fig. 3.

Extending downwardly from a forward portion of walls 17, 18, is a vertically disposed enlarged, dome shaped walled bracket 22. The bracket 22 communicates at its upper end with the passageway or channel 16. The bracket 22 comprises a base with an annular vertically disposed edge 23, which is in the plane of the outer face of wall 17. The bracket 22 furthermore comprises a centrally disposed thickened wall portion 24 through which extends a horizontally disposed opening 24a, for the purpose hereinafter appearing.

The flared portion 15 of housing 10 is formed on the inner side of its rim with a peripheral

recess 25 which receives a soft resilient annular gasket 26, suitably retained therein by adhesive or the like.

Extending forwardly from the inner surface of back wall 14, are parallel pairs of aligned, upper and lower projections 27, 28. The wall 14 is formed with a pair of spaced, horizontally disposed threaded openings 29, disposed between the projections 27, 28, for the purpose herein-after appearing.

The combined conduit and support 12 comprises an externally threaded nipple portion 30. Extending upwardly from portion 30 and vertically offset with respect thereto is a short tubular section 31. Extending from the tubular section 31 and in communicating relation therewith, is an enlarged, dome-shaped walled bracket 32, which is complementary in shape and size to the bracket 22 on housing 11. The base of bracket 32 comprises a vertically disposed annular edge portion 33 disposed opposite edge portion 23 on bracket 22. Extending from edge portion 33 is an annular lip 34 which projects into the annular opening formed by the edge 23 of bracket 22. An annular resilient gasket 35, such as rubber or the like, is mounted on the lip 34. The bracket 32 is formed with a centrally disposed thickened wall portion 36 through which extends a horizontally disposed opening 36a which is aligned with the opening 24a in bracket 22. A set screw or bolt 37 passing through the aligned openings and a nut 38 thereon, secure the brackets 22, 32 together, thereby forming an enclosed chamber therebetween. A lock washer 39 is on the screw or bolt 37, being disposed between the head thereof and the thickened wall portion 24. The housing 11 is thus adapted to be rotated or tilted with respect to the support 12 through the interfitting edges of the brackets 22, 32.

It is apparent that there is through communication between the interior of tubular member 13, through passageway 16, the chamber formed by brackets 22, 32, the offset tubular portion 31 and nipple 30.

A conventional floodlight socket 40 is coaxially mounted within tubular member 13, the rear portion thereof abutting the projections 27, 28. The socket substantially fills the rear portion of the housing and is secured in spaced relation to back wall 14 by headed screws 41, passing through the socket and received in threaded openings 29 in wall 14. Wiring 42, connected to the usual screw contacts on the rear of socket 40, runs parallel to the socket, being disposed in passageway 16 and extends through the chamber formed by brackets 22, 32, around screw or bolt 37 and continues downwardly through offset tubular portion 31 and nipple 30, as indicated in Fig. 3.

The nipple 30 is provided with a lock nut 43 whereby the supporting portion 12 of the floodlight assembly, may be suitably secured to a cross-arm, post, standard or the like.

It is apparent that the housing 11 may be tilted through an arc of substantially 180° to any one of a plurality of angular positions with respect to support 12, by unloosening nut 38 and moving the housing about pivot bolt or screw 37 to the desired position and tightening the nut to retain the housing in such position. The wiring 42 is fully enclosed within the housing, the pivotal connection as well as the support for the housing, thereby protecting it from the weather. The gasket 35 insures a close fit between the joint portions of brackets 22, 32, further rendering the joint weather proof.

The gasket 26 on the rim of the flared portion 15 of housing 11 which may be made of fibre, rubber, or the like, is adapted to seat exterior portions of a floodlight bulb, not shown, which is screwed into or otherwise mounted in socket 40. In this manner, the inserted lamp effectively seals off the interior of the housing against the ingress of water or the like. Furthermore, the compressibility of gasket 26 provides for the expansion of the floodlight bulb when the same becomes heated to its illuminating temperature, without cracking the glass of the bulb or impairing the waterproof seal at the rim.

In Fig. 5 is shown a pair of floodlight assemblies 10, embodying the invention, mounted on either end of a horizontal, hollow, cross arm 50, which in turn is supported on a hollow vertical post 51. The threaded nipple 30 of the support 12 may be suitably received in threaded openings in the upper surface of the cross arm 50 and the nuts 43 may be used to lock the support to the cross arm. It is apparent that the wiring 42 from each of the assemblies 10 may be extended from the nipple 30 into the hollow arm 50 and down through the post 51 to be appropriately connected to suitable power lines. Each of the assemblies may be tilted to a desired position and locked in such position, as previously described.

The housing 11 and support 12 may be made of cast metals or other materials which are weather proof and adapted to use for the purpose described.

It will thus be seen that there is provided a device in which the several objects of this invention are achieved and which is well adapted to meet the conditions of practical use.

As various possible embodiments might be made of the above invention, and as various changes might be made in the embodiments above set forth, it is to be understood that all matter herein set forth or shown in the accompanying drawings is illustrative and not in a limiting sense, except as set forth in the claims.

Having thus described my invention, I claim as new and desire to secure by Letters Patent:

1. In a floodlight lamp construction comprising a tubular body having an end wall and an outwardly flared open end opposite from said end wall, said end wall having perforations therein and having projections thereon extending forwardly within said body whereby a lamp bulb socket may be bolted against said projections within said body, said flared open end terminating in an annular recess receiving a yieldable gasket adhesively secured therein whereby a bulbous lamp bulb may impinge against the yieldable gasket to form a sealed joint, said body having a channel integral therewith depending therefrom and having its open side in direct communication with the interior of said body, said channel having an opening in its bottom portion along one end thereof, said channel having a depending wall integral therewith defining a continuation of said opening, said depending wall defining an outwardly concaved portion, forming a coplanar circular seat portion, said circular seat portion being adapted to cooperate with a complementary circular seat portion adapted to form a sealed joint when secured thereto by suitable fastening means, said channel and its openings, plus said concave portion providing ample space to receive electrically insulated conductors attachable to said lamp bulb socket.

2. The construction set forth in claim 1, in which the major portion of said tubular body is

cylindrical and the flared portion of said body being contoured to define a portion of a hollow spherical body.

3. In a floodlight lamp construction comprising a tubular one-piece body having an end wall constituting a closure integral with said body, said end wall having spaced projections thereon and integral therewith and extending forwardly within said body and constituting a seat for a lamp bulb socket adapted to be secured in said body, the major portion of said tubular body being cylindrical and having a flaring portion extending forwardly therefrom and terminating in a recessed circular rim, said recessed rim being adapted to receive a yieldable gasket, said body having a channel depending therefrom and integral therewith, the open side of said channel being in direct communication with the interior of said body, said channel having an opening in its bottom wall, said opening being located adjacent the lower central portion of said tubular body, said channel having a wall extending therefrom and being integral therewith, said wall being formed with a concaved portion defining a circular coplanar upright seat adapted to cooperate with a complementary upright seat when secured thereto by suitable fastening means, said channels, openings and concaved portion providing ample communicating space for insulated conductors attachable to said lamp bulb socket.

4. A lamp comprising a tubular housing having an integral end wall at one end thereof, and an integral flared portion at the other end thereof, said flared portion being formed with an annular recess on the interior of the rim portion thereof, a resilient annular gasket in said recess, a walled passageway integrally extending longitudinally from said tubular housing and in communication through its length with the interior of said housing, a dome shaped member integrally extending from one end of said passageway, the interior of said member communicating with said passageway, a support for said housing comprising a tubular member, a dome shaped member integrally extending from said tubular member, the interior of said second mentioned member communicating with said tubular member, said second mentioned member being complementary to said first mentioned member, and having base portions in opposed relation to base portions of said first mentioned dome shaped member, means connecting said members, said connected members forming a hollow chamber therebetween and adapted to provide for angular movement and adjustment of said housing with respect to said support about an axis transverse to the axis of said support, the end wall of said housing having projections extending into the interior of said housing, a lamp socket disposed within said housing abutting said projections, and means securing said socket to said housing, said passageway, chamber and hollow support being adapted to receive therein wiring for said lamp socket.

5. A lamp comprising a tubular housing having an end wall at one end thereof, and a flared portion at the other end thereof, said flared portion being formed with an annular recess on the interior of the rim portion thereof, a resilient annular gasket in said recess, a walled passageway extending longitudinally from said tubular housing and in communication with the interior of said housing through its length, a dome shaped member extending from one end of said passageway, the interior of said member communicating with said passageway, a support for said housing

comprising a tubular member, a dome shaped member extending from said tubular member, the interior of said second mentioned member communicating with said tubular member, said second mentioned member being complementary to said first mentioned member, and having base portions in opposed relation to base portions of said first mentioned dome shaped member, means connecting said members, said connected members forming a hollow chamber therebetween and adapted to provide for angular movement and adjustment of said housing with respect to said support about an axis transverse to the axis of said support, the end wall of said housing having projections extending into the interior of said housing, a lamp socket disposed within said housing abutting said projections, and means securing said socket to said housing, said passageway, chamber and hollow support being adapted to receive therein wiring for said lamp socket, the edge portions of one of said dome shaped members forming an interengaging lap joint with the edge portions of the other of said dome shaped members, and an annular gasket disposed between the interengaging portions of said members.

6. A lamp comprising a tubular housing having an end wall at one end thereof, and a flared portion at the other end thereof, a walled passageway extending longitudinally from said tubular housing and in communication with the interior of said housing throughout the length of said passageway, a dome shaped member extending from said passageway, the interior of said member communicating with said passageway, a support for said housing comprising a tubular member, a dome shaped member extending from said tubular member, the interior of said second mentioned member communicating with said tubular member, said second mentioned member being complementary to said first mentioned member, and having base portions in opposed relation to base portions of said first mentioned dome shaped member, means connecting said members, said connected members forming a hollow chamber therebetween, and said connecting means providing for angular movement and adjustment of said housing with respect to said support about an axis transverse to the axis of said support, a lamp socket disposed within said housing, and means securing said socket to said housing, said passageway, chamber and hollow support providing ample space to receive therein wiring for said lamp socket.

7. A lamp comprising a lamp holder having a substantially cylindrical portion, an end wall at

the rear end of said cylindrical portion and an outwardly flaring portion at the front end of said cylindrical portion, said holder being provided with a projection extending downwardly from said cylindrical portion, and said projection being formed with a passage communicating with the interior of the holder, said projection being provided with a hollow portion forming a recess opening to one side of said hollow portion, and communicating with said passage, and a support for said holder comprising a member having a hollow portion forming a recess facing and complementary to said first recess and forming a chamber therewith, and a tubular portion connected to said hollow portion by a portion having a passage communicating with the recess in the hollow portion of said supporting member, and means for interconnecting said hollow portions for relative rotation about an axis perpendicular to the axis of said cylindrical portion, said hollow portions of said projection and on said support having annular mouth portions, and said interconnecting means pressing said mouth portions together but providing for rotation of one hollow portion relative to the other, whereby said holder may be pivotally moved relative to said support, said holder being formed with a longitudinally grooved extension extending from said cylindrical wall and forming a channel interconnecting the passage which leads to the recess in the first hollow portion with the rear end of said holder.
